United States Patent Office

Des. 205,111
Patented June 21, 1966

205,111

MOBILE COUNTER FOR A BANK
Francis C. Kegel, 1738 Elmwood Ave., Kenmore, N.Y.

Filed Dec. 1, 1964, Ser. No. 82,856

Term of patent 14 years

(Cl. D80—2)

Fig. 1.

Fig. 2.

*Fig. 3.**Fig. 4.**Fig. 5.**Fig. 6.*FIG. 1 is a front perspective view of a mobile counter for a bank showing my new design the doors being in an opened position;

FIG. 2 is a rear perspective view of FIG. 1;

FIG. 3 is a front view;

FIG. 4 is a rear elevational view thereof, the doors being in closed position;

FIG. 5 is a top plan view of FIG. 4; and

FIG. 6 is a side elevational view of FIG. 4.

The dominant features of my design reside in the portions shown in full lines.

I claim:

The ornamental design for a mobile counter for a bank, substantially as shown and described.
